UNITED STATES PATENT OFFICE.

LEWIS O. HENGGI, OF OAKMONT, PENNSYLVANIA.

TIE-PLATE.

1,136,333.

Specification of Letters Patent. Patented Apr. 20, 1915.

Application filed August 25, 1914. Serial No. 858,510.

To all whom it may concern:

Be it known that I, LEWIS O. HENGGI, a resident of Oakmont, in the county of Allegheny and State of Pennsylvania, have invented a new and useful Improvement in Tie-Plates; and I do hereby declare the following to be a full, clear, and exact description thereof.

My invention relates to a combined tie-plate and anti-creepers for rails used in forming tracks for railways, and has for its object to provide a cheap, simple and efficient tie-plate and anti-creeper for such rails, which will not only connect such rail to the tie and thereby hold such rail on the tie and assist in preserving the tie, but will also prevent the longitudinal creeping or travel of the rail.

A further object of my invention is to provide such a combined tie-plate and anti-creeper which can be easily and cheaply manufactured, can be easily and quickly applied to the rails, will not be liable to become loosened or removed from the rails and will always form a binding action with such rails.

To these ends my invention consists, generally stated, in the novel arrangement, construction and combination of parts, as hereinafter more specifically set forth and described and particularly pointed out in the claims.

To enable others skilled in the art to which my invention appertains to construct and use my improved combined tie-plate and anti-creeper for rails, I will describe the same more fully, referring to the accompanying drawing in which:—

Figure 1 shows a top elevation of an ordinary railway rail and tie having my improved combined tie-plate and anti-creeper applied thereto. Fig. 2 is a side view of the tie showing the rail in position and in section. Fig. 3 is a side elevation of the rail in position. Fig. 4 is a plan of a sheet or plate from which my improved tie-plate and rail anchor blank is formed. Fig. 5 is a perspective view of one of the finished plates. Fig. 6 is a side elevation of the rail and tie showing another form of plate. Fig. 7 is a perspective view of the finished plate shown in Fig. 6.

Like symbols of reference herein indicate like parts in each of the figures of the drawing.

As illustrated in the drawing α represents

the ordinary approved form of a railway rail, which is provided with the usual head b , web c and base or flange d , and e is the usual form of wooden tie, which extends 60 across two of such rails to form this railway track (not shown), and under the flange d of the same to support such rails.

My combined tie-plate and rail anchor is shown at A and consists of the two plates 1, 65 which are of the same shape and size, and are preferably formed from sheet or plate metal, such as steel, by blanks B' being cut from the sheet or plate B , such as shown in Fig. 3 by dotted lines. These blanks B' so 70 formed are provided with the recessed portion b' within the body and on one side edge and with the projecting portion b'' within the body and on the other side edge opposite said recessed portion. The blanks B' are 75 pressed and punched to form the finished plates 1 in any suitable manner, and when so formed are provided with the raised portion 2 bent up at one end 1' of the same to form the recess or seat 2' under the same. A 80 clamping or lug portion 3 is bent up adjacent to the other end 1'' of the plate 1 and has a hooked end 3' thereon while a spike-hole 4 is formed in each of such ends, as well as a spike hole 4' is formed in body of 85 such plate and adjacent to said recessed portion. The lug portion 3 can be provided with a rib 3^a at its back to strengthen the same and such rib can be formed when the lug is punched and pressed up, while such 90 lug can also be dished, as at 3^b in order to form biting edges 3^c at each end of the same for taking into the top of the rail flange when the plates are brought to place as hereinafter described to further assist in holding 95 the plate and prevent creeping of the rail.

In placing my improved tie plate and rail anchor A in position in connection with the rail a and tie e , the plates 1 are inserted between the rail flange d and top of such tie 100 and with ends 1' and 1'' on such plates extending beyond said flange and longitudinally of the tie, so that the raised portion 2 on each plate will fit over the ends 1'' on each plate and such ends will thereby be 105 seated in the recesses 2' formed by said portions. The rounded edge portions in forming the recess portions b' and projecting portions b'' will thus enable the interfitting of said plates within each other by the ends 110 1'' on said plates fitting in the said recessed portions on one plate and against the edge

on said plate formed by said raised portion, while such projecting portions will extend out on each side of said tie plate and anchor A as formed along the rail flange d and 5 across the top of the tie e, so that a broad bearing surface will thus be given to the plate and anchor, when thus in position, the hooked end 3' of the lip portions 3 on the plates 1 will extend over both side edges of 10 the rail base or flange d and the under face of such portions are inclined or tapered, as at 3'' and on the same plane as the top face of such flange for the purpose hereinafter described. The spikes f can now be driven 15 into the tie e, through the holes 4 and 4', respectively, in the plates 1, and such spikes are first driven to place in the holes 4 and will act to draw such plates toward each other along said tie by such spikes engaging 20 the walls of said holes where they overlap each other in both plates. After such spikes are driven to place in the holes 4, the other spikes can be driven to place into the tie e through the holes 4' in each of the plate 1, 25 which will thus secure such plates forming the device A securely in position by assisting the spikes f, and it will be seen that in the movement of such plates toward each other during the driving of the spikes f in 30 the holes 4 the inclined portions 3 will ride up the top face of the rail base d and form a wedging or clamping action therewith to thus anchor the rail a on such device, while at the same time the functions of a tie plate 35 will be performed between the rail and tie by the securing of the plates in position as above described.

If desired, the plates 1 for my improved 40 combined tie-plate and rail anchor A may be formed of the shape shown in Fig. 6, which is cut in blank form from a plate or sheet such as B, shown in Fig. 4 in the same manner as the plate B', on which the projecting portion b'' on the plate B' will be 45 dispensed with and such side edge of the plate thus formed in a straight line, although, if desired, such projecting portion can be bent down for engagement with the side of the tie e, as shown in Fig. 6, which 50 will tend to prevent the tie plates from sliding across the tie, and when such plate is thus locked tight to the rail and the rail has any tendency to creep such creeping will be thus prevented. If desired the long end 55 of the plate 1 may be provided at its extreme end with a bent down portion 5 which presses into the tie and thus prevents any side movement of the rail b or plate 1.

Various other modifications and changes 60 in the design and construction of my improved combined tie-plate and rail anchor may be resorted to without departing from the spirit of the invention or sacrificing any of its advantages.

65 It will thus be seen that my improved

combined tie-plate and rail anchor will not only form a binding action upon the rail flanges to prevent the creeping of such rail but will also perform all the functions desired of the tie plates, and will be firmly and securely held between the rail and tie to hold the rail in position on the ties and also lessen the wear and cutting of the ties.

What I claim as my invention and desire to secure by Letters Patent is:

75 1. A tie-plate for railway rails, comprising two plates for fitting between the rail flange and tie, said plates interfitting with each other by a raised portion at one end of each plate fitting over the end of the other plate, each plate having a portion extending past the corresponding portion of the other plate, thereby to form a break-joint, said plates being provided with spike holes therein, and lug portions on said plates for engaging with the rail flange to form a clamping connection therewith when the plates are moved on each other by driving the spikes through said holes into the tie.

80 2. A tie-plate for railway rails, comprising two plates for fitting between the rail flange and tie, said plates interfitting with each other by being seated within each other and each plate having a portion extending past the corresponding portion of the other plate, thereby to form a break-joint, said plates being provided with spike holes therein, and lug portions on said plates each having a hook portion thereon for fitting over the rail flange to form a clamping connection therewith when the plates are moved on each other by driving the spikes through said holes into the tie.

85 3. A tie-plate for railway rails, comprising two plates for fitting between the rail flange and tie, said plates interfitting with each other by a raised portion at one end of each plate fitting over the end of the other plate, each plate having a portion extending past the corresponding portion of the other plate, thereby to form a break-joint, said plates being provided with spike holes therein, and lug portions on said plates each having a hook portion thereon for fitting over the rail flange to form a clamping connection therewith when the plates are moved on each other by driving the spikes through said holes into the tie.

90 4. A tie-plate for railway rails, comprising two plates for fitting between the rail flange and tie, said plates interfitting with each other by being seated within each other and each plate having a portion extending past the corresponding portion of the other plate, thereby to form a break-joint, said plates being provided with spike holes therein, and lug portions on said plates each having a hook portion thereon and provided with a tapered under face for fitting over and engaging with the tapered upper face

of the rail flange to form a clamping and wedging connection therewith when the plates are moved on each other by driving the spikes through said holes into the tie.

5. A tie-plate for railway rails, comprising two plates for fitting between the rail flange and tie, said plates interfitting with each other by a raised portion at one end of each plate fitting over the end of the other plate, each plate having a portion extending past the corresponding portion of the other plate, thereby to form a break-joint, said plates being provided with spike holes therein, and lug portions on said plates each 10 having a hook portion thereon and provided with a tapered under face for fitting over and engaging with the tapered upper face of the rail flange to form a clamping and wedging connection therewith when the 15 plates are moved on each other by driving the spikes through said holes into the tie.

6. A tie-plate for railway rails, comprising two plates for fitting between the rail flange and tie, said plates interfitting with each other and provided with spike holes 20 therein, lug portions on said plates for engaging with the rail flange to form a clamping connection therewith when the plates are moved on each other by driving the spikes 25 through said holes into the tie, and a downwardly projecting portion on one of said plates for fitting against the side of the tie.

7. A tie-plate for railway rails, comprising two plates for fitting between the rail flange and tie, said plates interfitting with each other by being seated within each other 30 and provided with spike holes therein, lug portions on said plates for engaging with the rail flange to form a clamping connection therewith when the plates are moved on each other by driving the spikes through 35 said holes into the tie, and a downwardly projecting portion on one of said plates for fitting against the side of the tie.

45. 8. A tie-plate for railway rails, comprising two plates for fitting between the rail flange and tie, said plates interfitting with each other by a raised portion at one end of each plate fitting over the end of the other plate, spike holes within said plates, lug 50 portions on said plates for engaging with the rail flange to form a clamping connection therewith when the plates are moved on each other by driving the spikes through 55 said holes into the tie, and a downwardly projecting portion on one of said plates for fitting against the side of the tie.

9. A tie-plate for railway rails, comprising two plates for fitting between the rail flange and tie, said plates interfitting with each other and provided with spike holes 60 therein, lug portions on said plates having a hook portion thereon for fitting over the rail flange to form a clamping connection 65 therewith when the plates are moved on each

other by driving the spikes through said holes into the tie, and a downwardly projecting portion on one of said plates for fitting against the side of the tie.

10. A tie-plate for railway rails, comprising two plates for fitting between the rail flange and tie, said plates interfitting with each other by being seated within each other and provided with spike holes therein, lug portions on said plates each having a 70 hook portion thereon for fitting over the rail flange to form a clamping connection therewith when the seats are moved on each other by driving the spikes through said holes into the tie, and a downwardly projecting portion on one of said plates for fitting against 75 the side of the tie.

11. A tie-plate for railway rails, comprising two plates for fitting between the rail flange and tie, said plates interfitting with 80 each other by a raised portion at one end of each plate fitting over the end of the other plate, spike holes within said plates, lug portions on said plates each having a hook portion thereon for fitting over the 85 rail flange to form a clamping connection therewith when the seats are moved on each other by driving the spikes through said holes into the tie, and a downwardly projecting portion on one of said plates for fitting 90 against the side of the tie.

12. A tie-plate for railway rails, comprising two plates for fitting between the rail flange and tie, said plates interfitting with each other and provided with spike holes 100 therein, lug portions on said plates each having a hook portion thereon and provided with a tapered under face for fitting over and engaging with the tapered upper face of the rail flange to form a clamping and 105 wedging connection therewith when the plates are moved on each other by driving the spikes through said holes into the tie, and a downwardly projecting portion on one of said plates for fitting 110 on one of said plates for fitting against the side of the tie.

13. A tie-plate for railway rails, comprising two plates for fitting between the rail flange and tie, said plates interfitting with each other by being seated within each other 115 and provided with spike holes therein, lug portions on said plates each having a hook portion thereon and provided with a tapered under face for fitting over and engaging with the tapered upper face of the rail flange to form a clamping and wedging connection therewith when the plates are moved on each other by driving the spikes through 120 said holes into the tie, and a downwardly projecting portion on one of said plates for fitting 125 against the side of the tie.

14. A tie-plate for railway rails, comprising two plates for fitting the rail flange and tie, said plates interfitting with each other by a raised portion at one end of each plate 130

fitting over the end of the other plate, spike holes within said plates, lug portions on said plates each having a hook portion thereon and provided with a tapered under face 5 for fitting over and engaging with the tapered upper face of the rail flange to form a clamping and wedging connection therewith when the plates are moved on each other by driving the spikes through said 10 holes into the tie, and a downwardly projecting portion on one of said plates for fitting against the side of the tie.

15. As a new article of manufacture, a tie-plate member comprising a sheet metal plate having stamped out therefrom toward one end an over-hanging lug portion for fitting over a rail flange, and being bent toward the other end to form an outwardly-extending up-set portion having a spike-hole 20 therein, the plate having a corresponding spike-hole at the opposite end.

16. As a new article of manufacture, a tie-plate member comprising a sheet metal plate having a widened portion at one end 25 and a restricted portion at the other end,

said widened portion having stamped out therefrom an over-hanging lug-portion for fitting over a rail flange, and said restricted portion being bent to form an outwardly-extending up-set portion having a spike-hole 30 therein, said widened portion being formed with a corresponding spike-hole.

17. As a new article of manufacture, a tie-plate member comprising a sheet-metal plate having a downwardly-bent tie-engaging portion at one side, and having stamped out therefrom toward one end an over-hanging lug-portion for fitting over a rail flange, said plate being bent toward the end opposed to said lug-portion to form an outwardly-extending up-set portion having a spike-hole 35 therein, the plate having a corresponding spike-hole at the opposite end.

In testimony whereof I, the said LEWIS O. HENGGLI, have hereunto set my hand.

LEWIS O. HENGGLI.
